BOAT HULL CONSTRUCTION

Albert W. W. van Hoorn, Holly Oak, Del.

Application November 2, 1938, Serial No. 238,326

10 Claims. (Cl. 9—6)

This invention relates to a new and improved construction for boats and to a process of making the same.

It is an object of this invention to devise a new and improved hull which can be constructed with greater ease and at less expense, with greater assurance of the proper form of the hull when completed and more particularly to devise a hull which is separated into a plurality of longitudinal sections or pods along planes parallel to the center line, whereby the separate pods may be easily constructed and easily assembled.

It is a further object to so simplify the construction and the method of making a hull that boats of medium size may be constructed by what may be relatively spoken of as quantity production without the individual attention required by previous methods.

It is a further object to provide a hull which, in case of accident to one or more pods can be completely repaired by replacing the damaged pod with an interchangeable unit of the same construction with a minimum of expense and time.

It is a further object to provide a hull which, if desired, may be sold and shipped in sections and readily assembled at the water front or at any convenient location either by an assembling crew or by an amateur without any difficulty in maintaining the symmetry of the lines.

It is a further object in the making of wooden boats to provide a method by which the parts of the skeleton may be made of sawn timbers instead of bent wood and which, nevertheless, will have all of the principal strains in the wood transverse to the grain.

It is a further object to provide a system of boat building by which a plurality of interchangeable sections may be provided for each of the several sections needed to build the boat, which sections may be assembled to provide a complete hull and in this manner a greater standardization of construction may be secured with a corresponding reduction in individual labor.

The invention accordingly comprises an article of manufacture possessing the features, properties, and the relation of elements which will be exemplified in the article hereinafter described and the scope of the application of which will be indicated in the claims.

For a fuller understanding of the nature and objects of the invention, reference should be had to the following detailed description, taken in connection with the accompanying drawings, in which:

Figure 1 is a side elevation of a hull constructed in accordance with this invention.

Figure 2 is a perspective view of a section of the hull as it is being built on the construction table.

Figure 3 is a center line cross section of the complete hull of Figures 1 to 3.

Figure 4 is a detail showing the dovetail connection between the rib sections and the longitudinal stringers.

Figures 5, 6 and 7 are views similar to Figures 2, 3 and 4 but showing the invention as applied to the construction of a hull with a metal frame.

Figure 8 is a detail of a clamping means suitable for use in holding the longitudinal stringers on the table.

Figure 9 is a side elevation of a hull of larger size embodying the invention.

Figure 10 is a central longitudinal section of the hull of Figure 9.

Figures 11 and 12 are detail sections of alternative constructions along the line 11—11 of Figure 9.

In the construction of boats it has been proposed to set upon the construction floor the keel and then attach a plurality of cross members or ribs to the keel holding the free ends in place by braces attached to them while the planking is nailed in place. In accordance with such a

system, the attachment of the planks, which have to be bent to shape, exerts sufficient force against the ribs to bend the ribs out of shape unless special care is taken to the contrary, and so requires a very careful bracing of the ribs. The attachment of the planks is usually commenced at the keel and in order to prevent the warping of the hull, the two sides are built up simultaneously by attaching to the ribs one or more planks on one side of the keel and then a substantially

equal number on the other side. This presents difficulty for as the keel rests on the floor, the installing or fastening of the first few planks is a difficult task and, the ribs themselves being all bent, materially tend to change their shape and

hence to deform the hull. Such construction is expensive and two hulls made from the same blue prints may in fact differ in shape. Attempts to use sawn ribs in place of bent ribs are not satisfactory under such a system since the different parts of the rib lie at such different angles to each other that at least at some point the strains will be across the grain of the wood.

Sometimes this system is modified by inverting the hull and building it with the keel up. This offers many of the same difficulties as in the pre-

ceding system, the hull itself being in the way of the workman, making it difficult to fasten the planks on the skeleton.

In accordance with this invention the hull is divided by a series of planes intersecting in a line along the center of the boat, thus forming longitudinal sections which I prefer to call pods. Each of these pods is defined by a longitudinal member on each edge, herein referred to as a stringer, and between these stringers transverse to them, extend sections of ribs which are firmly fastened to them.

In constructing larger hulls each of these pods may in turn be divided transversely to make sections easy to handle and construct and in any case the reinforcing members which run along the edges of the pods or sections furnish a practical point of attachment for transverse reinforcing or deck supporting beams. If desired a plate may be clamped between the pods to give greater stiffness or afford better means of support.

Referring now to the drawings and in particular to Figures 1 and 3, the hull, as shown, is formed of four pods 10, 11, 12 and 13 which meet along planes AB, AC and AD. These planes intersect along a line A, as seen in Figure 3, which line extends from the bow to the stern of the boat along the center line of the hull. Each meeting edge of the pods is provided with a longitudinal stringer aligned in the intersecting plane and having a contour conforming to the shape of the hull along the line of intersection of that plane with the hull. Thus the pod 10 has at its upper edge a deck shelf or stringer 14 and the pods 10 and 11 at their plane of intersection are provided with bilge stringers 16 and 17 respectively, which, because each lies in the plane of intersection and each conforms to the hull form, may be caused to lie flat against each other as shown.

The pods 13 and 12 correspond respectively to the pods 10 and 11, but of course are reverse to them. The pod 13 having a deck shelf or stringer 18 and the pods 12 and 13 meeting along a bilge stringer 20 and 21. The pods 11 and 12 have along the meeting edges check pieces or keel stringers 22 and 23, which are provided with the dovetails into which the rib sections are fitted. These keel stringers are fastened to keel sections 22a and 23a each of which forms one half of the permanent keel. The pods 11 and 12 being fastened with bolts which in the center of the boat, fore and aft, may pass through the check pieces and through the keel sections but at the ends of the boat may pass through the keel and stern sections only. This division of the keel facilitates cutting the keel to provide a shaft alley for the propeller shaft. With this construction this can be cut by merely grooving the half keels.

These sections or pods are built together to form the complete hull, being fastened by bolts 28 or other suitable means. If desired, there may be interposed between them a sheet of packing material adapted to insure a tight joint at the connection.

One of the particular advantages of this type of construction is the ease with which the separate pods may be built and this will now be described by reference to Figures 2 and 4. I have chosen to illustrate this construction in connection with the construction of pod 10 but the other pods have the same construction, except for the shape and they are constructed in the same manner.

The numeral 30 designates a table or bench of a suitable height to make all parts of the con-

struction accessible. Upon the surface of this table is marked the contour of, for example, the bilge stringer 16 and the stringer is fastened flat upon it with the edge of the stringer that is to meet the adjacent stringer flat upon the table. As illustrated, there is provided upon the table a series of holes corresponding to the holes in the stringers, which are to receive the fastening bolts 28 in the stringer 16 and the stringer itself is fastened to the table by bolts passing through these holes, being thus not only firmly held to the table but also firmly held against being bent out of shape by the attachment to the planks as the latter are applied.

In Figure 8 is shown an alternative construction in which the holes in the table are on one side of the stringer and the stringer is held to the table by J shaped claimps 28a having a stem 28b fitting within the holes, and having the short leg of the J 28c bearing against the stringer. Such a clamp will hold tightly when driven into its hole, but will readily release if knocked sideways by a hammer.

The stringer 16 itself is provided upon its upper side as it lies upon the table, with a series of dovetail slots 31 corresponding to the location of the rib sections to be attached. These slots are all parallel and each of them is perpendicular to the center line of the boat and parallel to the plane AE.

In the construction here shown the deck shelf or stringer 14 is not continuous but is composed of two sub-stringers 14a and 14b at different levels from each other. The former extending along the fore part of the boat and the latter along the stern portion; the difference in level being in accordance with the design of the hull to be formed. Each of these sub-stringers 14a and 14b is provided with a series of dovetail slots 32 cut on its underside opposite the slots in the bilge stringers 16 and thus corresponding to the position of the upper edge of the rib section of the skeleton. These slots, as in the case of the slots in the bilge stringers, are all parallel to each other and parallel to the horizontal in the form in which the section finally lies in the hull.

At the point where the two sub-stringers overlie, as shown at 14c, a special construction may be provided, if desired, thus short spacing sections 14d may be used to keep the over-lying sections properly spaced from each other.

After the bilge stringer is fastened to the table, as above described, the upper or sub-stringer 14a is held in place by attaching its front portion to the stem section 34 and by inserting one of the ribs 35 near its stern end into a dovetail 31 in the bilge stringer and into a dovetail 32 in the deck shelf simultaneously. The sub-stringer 14b may be similarly held in place by ribs 36 and 37 respectively. Whereupon the remaining ribs 38 may each, one by one, be forced into the slots at top and bottom by suitable pressure, they being particularly designed to fit very tight. They are preferably forced into place by pressure, as for example by clamps, and when in place they form a very rigid skeleton frame which is rigidly supported from the table.

If the angularity between the terminal planes of the pod is not great, it is possible to make the dovetails 31 and 32 parallel to each other, which greatly facilitates inserting the stringer in the dovetail.

The construction offers so great rigidity that the planks may be nailed directly to the skeleton thus formed without special precautions, at least

in medium sized boats; the ribs themselves being rigid enough to take the strain.

As soon as the planks on the top and bottom edge of the pod have been nailed in place, being attached as they are both to the stringers and to the ribs, they serve as a means of holding the rib dovetailed tongue from sliding in the dovetail slot, thus further rigidifying the whole.

By this construction the pod is substantially upright while it is being constructed, which greatly facilitates the shaping of the planks to the skeleton and renders all parts easily accessible to the workmen.

Moreover, by reason of the fact that within the width of a single pod the change in angularity of the hull cross section is not great, it is possible to saw the rib sections to shape without materially weakening them without running into a cross grain. When the pod 10 has been completed it may be removed from the table by removing the bolts 38 and thereafter the remaining pods may be built. It may be observed that in its contour and bolt positions the lower bilge stringer of the pod 10 is identical with the upper bilge stringer of the pod 12 and the upper bilge stringer of the pod 11 is identical with the lower bilge stringer of the pod 13, so that for the complete construction of the four pod hull it would be necessary to have two sets of markings only on the table.

When all of the sections have been built as described, the four pods are bolted together to form a compete hull. Preferably, the keel stringers 22 and 23 are so designed as to engage the side faces of the keel 46 so that a single set of bolts may bolt the lower pods and the keel together.

In the form of the invention disclosed in Figures 5, 6 and 7, the general division of the hull and the assembly is identical with that which has been described, except that the stringers in the rib sections are of metal and the ribs are welded to the stringers as shown in Figure 7 in place of being dovetailed into them as in the case where wood is used. The skin itself may be made of any suitable material but in any event it will be seen that the same easy assembly will be found in the construction as in the first embodiment of the invention because of the ready accessibility of the parts.

In the form of the invention disclosed in Figures 9 to 12 the invention is shown as applied to the construction of a larger hull, as for example a metal tanker and as there shown the hull may be divided by transverse planes FF and GG as well as by the planes parallel to the center line as in the previous modification. Thus each of the pods H, I, J, K, L or M is divided into a series of sections H1, H2, etc., at these transverse planes.

These pod sections H1, H2, etc., may be bolted together by bolts extending through the terminal ribs thereof as shown in Figure 11 or, if desired, transverse plates N may be inserted between the flanges of adjacent ribs to be bolted to both ribs thus furnishing a rigid reinforcing member to strengthen the hull at that point.

In the construction of many steel hulls the body of the boat has parallel sides so that during all of the intermediate hull sections the ribs will be vertical and the plates attached directly thereto without the necessity of bending.

The cross beams and the deck supporting beams may be attached, if desired, to the longitudinal stringers or to the adjacent rib sections

where the pod sections are connected together. This method of assembly greatly facilitates the building of large hulls.

By the above construction it will be seen that the hull can be readily constructed and assembled. Moreover, because of the form of the construction, all of the elements may be formed of sawn members making it unnecessary to bend the wood to shape and relieving the hull of the strains imposed by the gradual distortion of the bent members when released from the strain.

Since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent, is:

1. A skeleton for a hull, said hull being of the type having progressively curved sections throughout, said skeleton comprising a plurality of curved stringers extending in a direction from stem to stern and curved to conform to the shape of said hull, said stringers being arranged in pairs, a plurality of curved rib sections extending from each of said stringers to the other stringer of said pair and having both ends of each of said rib sections firmly attached to said stringers to form a pod frame conforming to a portion of the curved contour of the hull, said skeleton being of such strength as to resist the strains incident to the bending of the skin surface from the flat to the progressively curved contour of the hull, the adjacent stringers of adjacent pod frames having longitudinal surfaces lying in a plane substantially parallel to the center line of the hull and being attached together along said plane throughout their lengths to join said frames to form a hull skeleton.

2. A device in accordance with claim 1 having a skin surface over said hull skeleton firmly attached to said stringers and to said ribs at the joint between them, whereby the said joint is firmly reinforced by said skin.

3. A device in accordance with claim 1 in which there are provided two such pod sections on each side of the longitudinal vertical center line of the boat, the adjacent stringers of each of said two pod sections contacting along a plane inclined to the vertical and being firmly bolted together.

4. A device in accordance with claim 1 in which the means of attaching each stringer to each rib comprises a dove-tailed joint, each joint of one stringer being substantially parallel to the corresponding joint of the other stringer, whereby each rib section may be forced into place along said joints without displacing said stringers.

5. A pod for a hull, said hull being of the type having progressively curved sections, said pod comprising a pair of stringers, each curved throughout its length to correspond to the section of the progressively curved hull along a

plane substantially parallel to the center line of the hull, one of said stringers being constructed and arranged to be joined to an adjacent stringer of an adjacent pod section on one of said planes to form a hull and having a terminal surface conforming to said plane, said stringers being spaced apart in substantially parallel relation, a plurality of rib sections, each curved to conform to the progressively curved contour of the hull and extending from one of said stringers to the other and having each end firmly attached to its corresponding stringer, said ribs comprising the means by which said stringers are connected together to form a pod frame, said rib sections being of such strength and so firmly attached to said stringers as to hold the said pod frame to the hull contour, independent of other support and a skin surface bent about the skeleton formed by said ribs and stringers, from the flat, and retained in said progressively curved contour by such skeleton.

6. A pod for a hull, said hull being of the type having progressively curved sections, said pod comprising a pair of stringers each curved throughout its length to correspond to the skin of the hull along a plane substantially parallel to the center line of the hull, one of said stringers having a plane terminal surface substantially conforming to one of said planes, said stringers being spaced apart and substantially parallel to each other, a plurality of curved rib sections each conforming to the contour of the hull and extending from one of said stringers to the other, said ribs comprising the means by which the stringers are connected together, a skin surface fastened upon the exterior of the skeleton formed by said ribs and stringers, said rib sections being of such strength and so firmly attached to said stringers to hold the said pod skeleton to the hull contour without other support even against the strains imposed by the bending of said skin from the flat to the curved contour of the hull.

7. A device in accordance with claim 6 in

which the means of attaching each stringer to each rib comprises a dove-tailed joint, each joint of one stringer being substantially parallel to the corresponding joint of the other stringer, whereby each rib section may be forced into place along said joints without displacing said stringers.

8. A device in accordance with claim 6 in which the means of attaching each stringer to each rib comprises a dove-tailed joint, each joint of one stringer being substantially parallel to the corresponding joint of the other stringer, whereby each rib section may be forced into place along said joints without displacing said stringers, and a skin surface laid over the ends of said dove-tailed joints and firmly joined to said ribs and to said stringers at said joint, whereby said ribs are held in said dove-tailed joints by said skin.

9. A skeleton for a hull of the type having progressively curved sections throughout formed about a skeleton, said skeleton comprising a plurality of sections on each side of the vertical center plane of the hull extending in the direction from stem to stern, each comprising a self-supporting frame, each of said sections having a longitudinal stringer curved to correspond to the curvature of the hull, on each edge thereof, and a plurality of rib sections also curved to correspond to the curvature of the hull extending between and firmly attached to said stringers to form with said stringers a self-supporting hull section, the adjacent stringer of the hull sections on each side of the said center plane lying in a common plane parallel to the center line of the hull and being firmly attached together to form said hull.

10. A device in accordance with claim 1, having a skin surface over said skeleton and firmly attached thereto comprising a plurality of individual horizontal strips bent to conform to the progressively curved section of the skeleton.

ALBERT W. W. VAN HOORN.
